ABSTRACT OF THE DISCLOSURE

Operation of a process to recover H_2S and NH_3 from an aqueous solution of H_2S , NH_3 , and light hydrocarbons under superatmospheric pressure, wherein the H_2S and NH_3 are recovered separately from an H_2S stripper and an NH_3 stripper, respectively, is improved from a control and stability standpoint, and aqueous feed solutions of high H_2S content are more advantageously handled by (1) combining an NH_3 -rich, H_2S -lean condensate stream generated in the overhead system of the NH_3 stripper with the aqueous solution of NH_3 , H_2S , and light hydrocarbons; then (2) removing light hydrocarbons as gases by reducing the pressure on the combined solution; (3) providing residence time for the combined solution; and then (4) feeding the combined aqueous feed stream to the H_2S stripper.

BACKGROUND OF THE INVENTION**Field of the invention**

This invention relates to methods for recovering H_2S and NH_3 from aqueous streams containing the same. More particularly, this invention relates to processes for separately recovering H_2S and NH_3 from aqueous streams.

Description of the prior art

In many hydroconversion processes applied to hydrocarbon oils, shale oil, tar sands, etc. of which catalytic hydrogenation, hydrofining or hydrodesulfurization and hydrocracking are typical examples, H_2S and NH_3 are produced as a result of reaction of hydrogen with sulfur compounds and nitrogen compounds contained in the oil. Sometimes this conversion of one or the other or both of the sulfur and nitrogen compounds is the desired reaction, while in other cases it is merely an incidental reaction. In a typical process, normally liquid hydrocarbon oil containing nitrogen compounds and sulfur compounds and recycle hydrogen-rich gas and makeup hydrogen are passed through a reaction zone, usually containing a catalyst, at elevated temperature and pressure at which at least a portion of the hydrocarbons are vaporized; and there is obtained as a reaction zone effluent a mixture of vaporized hydrocarbons, hydrogen, H_2S and NH_3 . The effluent may also contain heavier hydrocarbons which are liquid at the reaction conditions. The reaction effluent is cooled to condense vaporized hydrocarbons, whereby the liquid hydrocarbons can be separated from hydrogen-rich recycle gas, which is then reused in the process.

When the reaction effluent contains both H_2S and NH_3 , it has been found that on cooling to temperatures below about 300° F. the H_2S and NH_3 may react to form salts which sometimes cause clogging problems in the heat exchangers and the lines. Injection of water into the reaction effluent upstream of the heat exchangers has been used to wash out such deposits and/or to prevent their forming. This water injection can provide a means of removing much of the NH_3 formed, if rather large amounts of water are injected sufficient to dissolve the NH_3 .

2

In a typical hydroconversion process, such as hydro-treating or hydrocracking, there are considerable amounts of light hydrocarbons and hydrogen present in the reaction effluent. Upon washing H_2S and NH_3 out of the reaction effluent, particularly if the washing is at a high pressure. In many hydroconversion processes, the washing is done at a pressure of 500 to 5,000 p.s.i.g., more well as a small portion of the hydrogen, will dissolve in action effluent, a portion of these light hydrocarbons, as typically 1,000 to 3,000 p.s.i.g. For example, in hydro-treating gas oil, the effluent from the hydrotreater typically is cooled by heat exchange to a temperature between about 100 and 150° F. at a pressure of 2,000 p.s.i.g. Because the water is mixed with the gaseous effluent from the hydrotreater reactor at high pressure and before the effluent is cooled to 100 to 150° F., significant amounts of light hydrocarbons, such as methane, ethane, propane, butane, etc., will dissolve in the water.

These light hydrocarbons, as well as dissolved hydrogen, may be removed from the aqueous phase prior to treatment to remove H_2S and NH_3 by reducing the pressure on the aqueous solution. It is desirable to retain H_2S in the aqueous solution when the pressure is reduced because (1) the H_2S is an impurity in the light hydrocarbon vapors; and (2) the H_2S is preferably recovered in a single concentrated stream as a valuable byproduct in a subsequent H_2S and NH_3 recovery process. However, in many instances, the content of H_2S in the aqueous solution which is formed—e.g., in the overhead system of strippers or fractionators associated with hydroconversion processes—is too high for the H_2S to be substantially completely retained in the solution when the pressure is reduced.

Another problem that exists according to previous methods to recover H_2S and NH_3 separately from foul water containing the same resides largely in obtaining steady and stable control of the strippers used to recover H_2S and NH_3 , respectively. In the process described in U.S. Pat. 3,335,071 issued to W. M. Bollen et al. and assigned to Chevron Research Company, an aqueous solution of H_2S and NH_3 may be treated according to the following steps:

(a) Stripping the NH_3 , H_2S aqueous solution in a first stripping distillation column to obtain as an overhead an H_2S -rich vapor and as bottoms an NH_3 -rich aqueous bottoms solution;

(b) Stripping the NH_3 -rich aqueous bottoms in a second distillation column to obtain an NH_3 -rich vapor overhead;

(c) Partially condensing the NH_3 -rich vapor overhead to obtain an NH_3 -rich vapor and an NH_3 -rich aqueous overhead condensate; and

(d) Recycling a portion of the NH_3 -rich aqueous overhead condensate to the first distillation column (the H_2S stripper).

The disclosure of U.S. Pat. 3,335,071 is incorporated by reference into the present specification.

Recycling the NH_3 -rich overhead condensate to the H_2S stripper is highly desirable for some purposes, but fluctuations in the NH_3 content in this stream tend to cause periodic upsets in the H_2S stripper operation. This is thought to be partly due to the considerable amounts of NH_3 contained in the recycle relative to the amount of NH_3 in the feed to the H_2S stripper. Although it is not completely understood why, in some instances when the NH_3 content of the NH_3 stripper overhead condensate increases, a large "bubble" of NH_3 would travel up the H_2S stripper reducing the purity of the H_2S overhead and requiring adjustment in the overhead control in the H_2S stripper. Also, increases in NH_3 content of the recycle NH_3 stripper overhead condensate result in higher pres-

sures being required at the bottom of the H_2S stripper when operating at a given temperature. Because these changes would occur relatively rapidly, steady and stable control of the H_2S stripper and NH_3 stripper was not always attainable.

In summary, according to practices employed under the prior art, considerable amounts of H_2S may be lost from the aqueous solution desired to be treated for separate recovery of H_2S and NH_3 when the pressure is reduced on the aqueous solution so as to remove light hydrocarbons and/or hydrogen dissolved in the aqueous solution of H_2S and NH_3 . Also, according to previously employed methods for separately recovering H_2S and NH_3 , difficulties are incurred in attempting to obtain steady and stable operation of the H_2S and NH_3 strippers. In the process of the present invention, these problems are substantially overcome.

SUMMARY OF THE INVENTION

According to the present invention, in a process for separately recovering H_2S and NH_3 from a first aqueous solution comprised of H_2S , NH_3 , and light hydrocarbons under superatmospheric pressure according to the steps:

(a) Degassing the first aqueous solution by reducing the pressure, thereby removing light hydrocarbons and obtaining a second aqueous solution comprised of H_2S and NH_3 ;

(b) Stripping H_2S out of the second aqueous solution in a first distillation column to obtain an H_2S -rich overhead stream and an aqueous bottoms stream of reduced H_2S content;

(c) Stripping NH_3 out of the aqueous bottoms stream in a second distillation column to obtain an NH_3 -rich vapor overhead; and

(d) Partially condensing the NH_3 -rich vapor overhead to obtain an NH_3 -rich vapor and an NH_3 -rich overhead condensate.

The improvement is made which comprises:

(e) Combining at least a portion of the NH_3 -rich overhead condensate with the first aqueous solution to obtain a combined aqueous solution; then

(f) Removing at least a portion of the hydrocarbons contained in the first aqueous solution in a degassing zone as vapors by reducing the pressure on the combined aqueous solution to obtain said second aqueous solution; and then

(g) Passing the second aqueous solution to the first distillation column.

Operating in this manner avoids direct recycle of the NH_3 stripper overhead condensate to the H_2S stripper; and improved control and stability of the H_2S stripper is obtained. In addition, the recycle of the NH_3 -rich overhead condensate from the NH_3 stripper to the degassing zone serves to retain H_2S in the aqueous phase while degassing light hydrocarbons and/or hydrogen from the aqueous feed containing the H_2S - NH_3 .

The improved stability of the H_2S stripper is thought to be largely a result of avoiding direct recycle of NH_3 -rich condensate. According to the present invention, the NH_3 -rich condensate is recycled to the degassing zone where it achieves or closely approaches equilibrium with the net feed to the H_2S stripper; and fluctuations in the feed composition are damped out due to the extra residence time. A residence time of at least five minutes after combining the aqueous streams and prior to introduction to the H_2S stripper is desirable. Much more preferable, a residence time of about one to three hours is provided for the combined gross feed streams of recycle NH_3 -rich condensate from the NH_3 stripper and net H_2S - NH_3 aqueous feed solution. Still more preferable, a residence time of between about 3 and 24 hours or longer is provided for the combined, that is gross, feed streams. Provision for residence time for the recycle NH_3 -rich condensate prior to introduction to the H_2S stripper is in contrast to previous operation wherein the recycle of

NH_3 -rich condensate directly interconnected the H_2S stripper and the NH_3 stripper so that upsets in either of these strippers could often affect the other stripper.

Also, it has been found that, if a residence time of about 24 hours or longer is used, then oil may be essentially completely separated from the foul water feed streams so that the strippers are kept cleaner. Additionally, when the feed streams include foul water from fluid catalytic cracking units or the like, the residence time of about 24 hours or longer will allow hydrocyanide acids which are likely to be present in such foul water streams to be converted to thiocyanate. Conversion of the hydrocyanide to thiocyanate helps minimize corrosion problems in the strippers.

15 It has been found that with the recycle of the NH_3 overhead condensate large amounts of H_2S in the aqueous feed streams to the present process may be dealt with without excessive losses of H_2S in the light hydrocarbons and/or hydrogen from the degassing step. Under most conditions, the H_2S content of the gases from the degassing step is very low. The degasser off-gases may be used as refinery fuel gas as only a very small amount of SO_2 will be produced by burning the gases. Thus air pollution is substantially reduced.

20 25 A number of streams containing H_2S and/or NH_3 may be treated in the process of the present invention, but it is preferable that there be a vessel or some means to provide residence time and allow mixing of the NH_3 -rich condensate and the net feed to the present process.

30 35 For example, there may be provided simply a surge vessel with no removal of light hydrocarbons or a degasser to remove light hydrocarbons from at least one of the feed streams to the present process. In the more usual case, it is necessary to provide a degassing step which in many instances results in loss of H_2S and/or extra expense to remove H_2S from the light hydrocarbons when not using the process of the present invention. As indicated above, the H_2S contents of the net feed streams may be relatively high in the present process but still dealt with without large H_2S losses or H_2S impurities in the degasser zone off-gases. The recycle of the NH_3 stripper overhead condensate to the degasser zone serves to retain H_2S in the aqueous phase.

40 45 In the process of the present invention, it has been found that it is advantageous to use two stages of degassing. Use of two stages of degassing serves to further minimize the H_2S losses in the light hydrocarbon streams which are removed from the aqueous solution when the pressure is reduced on the aqueous solution in the degassing zone. The first stage of degassing is a high pressure degassing stage wherein the pressure is maintained between 50 and 500 p.s.i.g. Preferably the pressure is maintained at about 70 to 200 p.s.i.g. The liquid phase aqueous solution from the high pressure degassing stage is then passed to a low pressure degassing stage.

50 55 Aqueous streams containing H_2S and/or NH_3 together with small amounts of light hydrocarbons, which light hydrocarbons are dissolved in the aqueous solution due to relatively low pressures, for example, 10 p.s.i.g. to 60 65 100 p.s.i.g., are advantageously introduced to the process of the present invention by combining such streams with the aqueous solution fed to the low pressure degasser. The low pressure degasser is maintained at a pressure between 0 p.s.i.g. and 50 p.s.i.g., preferably between 1 p.s.i.g. and 10 p.s.i.g.

BRIEF DESCRIPTION OF THE DRAWING

The drawing schematically illustrates a preferred embodiment of the present process for separately recovering H_2S and NH_3 , wherein two degassing stages are used.

DETAILED DESCRIPTION OF THE DRAWING AND THE INVENTION

70 Referring now in more detail to the drawing, an aqueous feed stream containing H_2S and NH_3 is intro-

duced to the process via line 1. In a preferred embodiment of the present invention, this aqueous feed stream is obtained by commingling or contacting the effluent from a hydrocracking reactor at a pressure of about 2,000 p.s.i.g. with water. As indicated in the discussion under "Background of the Invention," this contacting is carried out to remove ammonia and H_2S from the hydrocracker reactor effluent. Because the hydrocracker reactor effluent contains substantial amounts of hydrogen and light hydrocarbons, the aqueous solution which is formed is comprised of hydrogen and light hydrocarbons in addition to H_2S and NH_3 .

In the process of the present invention, this aqueous solution is combined with the recycle NH_3 -rich aqueous stream obtained from the overhead of the NH_3 stripper, as will be described in more detail hereinbelow. The NH_3 -rich aqueous solution is recycled via line 26.

A stream rich in H_2S obtained from the overhead of one of the stripping distillation columns used to remove light hydrocarbons from the hydrocracker effluent product is introduced to the process via line 2. Among the many H_2S -rich streams that may be treated in the process of the present invention are those streams derived from steam stripping liquid hydrocarbon effluents from hydro-treating or hydrofining processes. These liquid hydrocarbon effluents contain H_2S and light hydrocarbons which are removed by stripping or distillation. The stripper or distillation column overhead vapors which result from the stripping operation contain appreciable amounts of H_2S which dissolve to a significant extent in the water formed when the overhead is partially condensed. Frequently the stripping is carried out at low pressures, for example, 5 to 50 p.s.i.g., in the overhead accumulator. In this instance, these overhead condensate streams may be introduced to the process of the present invention via line 7. It is particularly important to remove light hydrocarbons from the overhead condensate streams when the H_2S , which is removed from the H_2S stripper via line 15, is desired in a highly purified form. For example, when the H_2S is to be used as feed to a Claus process for manufacture of sulfur, it is desirable that the H_2S stream contain less than 0.1 volume percent hydrocarbons.

In some instances, the hydrocarbon effluent from the hydrotreating or hydrocracking process will be stripped or fractionated to remove H_2S and light hydrocarbons at a pressure above 50 p.s.i.g. For example, in U.S. Pat. 3,356,608, a process is described wherein gas oil and hydrogen are contacted with a sulfactive hydrogenation catalyst and the effluent hydrocarbon stream, after separation of recycle hydrogen, is steam stripped at pressures above 150 p.s.i.g. Upon condensing the overhead from the stripper, an aqueous phase is formed which may be very rich in H_2S compared to aqueous solutions formed in the presence of H_2S at lower H_2S partial pressures.

Referring again to the drawing, the combined streams 1, 2 and 26 are introduced via line 3 to the high pressure degasser 4. In order to achieve low H_2S contents in the off-gases, the high pressure degasser is preferably maintained at a pressure of about 185 p.s.i.g. and a temperature of about 80° F. Lower pressures and higher temperatures will result in increased H_2S contents in the off-gas. Light hydrocarbons and hydrogen are removed via line 5 from the top of the high pressure degassing vessel. When operating at about 100 to 200 p.s.i.g. and 80 to 100° F., the H_2S content of stream 5 is generally less than 3 volume percent. When operating at high pressure and low temperature for the high pressure degasser in accordance with the present invention, the H_2S content may be maintained between about 0.1 to 2.0 volume percent. Thus stream 5 has a very low H_2S content and is generally suitable as refinery fuel gas. The partially degassed aqueous solution is withdrawn from the bottom of the high pressure degasser via line 6.

An aqueous solution of H_2S , NH_3 and small amounts of

dissolved hydrocarbons, which aqueous solution is obtained as overhead condensate from a hydrocarbon stripper operating at an overhead pressure of about 50 p.s.i.g., is introduced via line 7. The combined aqueous streams in lines 6 and 7 are passed via line 8 to low pressure degasser 9. The low pressure degasser is preferably maintained at a pressure of about 2 p.s.i.g. Light hydrocarbons are withdrawn in line 10 from the low pressure degasser, and an aqueous solution of H_2S and NH_3 is withdrawn from the bottom of the degasser via line 11. The H_2S content of stream 10 is generally less than about 4 volume percent when operating in accordance with the present invention. The percent of H_2S in the low pressure degasser off-gases may be reduced further, for example, to the range for the high pressure degasser, by increasing the amount of NH_3 -rich condensate and by lowering the temperature and raising the pressure. In most instances, the major portion of the off-gases, which are mostly hydrogen and methane, are released in the high pressure degasser. Usually about 80 to 90 volume percent of the dissolved gases flash off in the high pressure degasser. Therefore, there is only a relatively small quantity of H_2S carried off with the off-gases from the low pressure degasser. Thus, in accordance with the present invention, nearly all the H_2S is left in the aqueous phase so that it may be recovered as one overhead stream from the H_2S stripper.

The aqueous solution from the low pressure degasser is introduced to feed surge tank 12 wherein a residence time preferably between 3 and 24 hours is provided. The feed surge tank 12 should be a floating roof tank or inert gas blanketed. If air is allowed to come in contact with the aqueous solution, hydrogen sulfide will be oxidized to form free sulfur.

Aqueous solution is withdrawn from the feed surge tank via line 13 and introduced to H_2S stripper 14. Due to heat input in the bottom of the H_2S stripper, hot upflowing vapors are generated which serve to strip H_2S out of the aqueous solution. A cool stream of water is introduced via line 16 to the upper part of the H_2S stripper so as to generate a downward flowing aqueous stream which serves to fractionate the NH_3 from the H_2S . A relatively pure stream of H_2S is withdrawn via line 15 from the top of the H_2S stripper. The NH_3 content in this H_2S stream is usually less than 2 weight percent, commonly as low as a few tenths of a percent; and preferably the H_2S stripper conditions are maintained so as to result in an NH_3 content of less than 100 p.p.m., for example, 10 to 30 p.p.m.

An aqueous solution which is rich in NH_3 but still containing substantial amounts of H_2S is withdrawn via line 17 from the bottom of the H_2S stripper. This stream is fed to NH_3 stripper 18. Hot upflowing vapors are generated by heat input into the bottom of the NH_3 stripper. These hot upflowing vapors serve to strip NH_3 and H_2S out of the aqueous solution fed to the NH_3 stripper. A purified water stream is withdrawn from the bottom of the NH_3 stripper via line 19.

A vapor stream comprised of H_2O , NH_3 , and H_2S is withdrawn from the top of the NH_3 stripper via line 20. The operating conditions in the NH_3 stripper are controlled so as to regulate the amount of H_2O in the vapor stream in line 20 so that, when this vapor stream is partially condensed in condenser 21, the liquid condensate formed and withdrawn from the condenser in line 22 will contain a very large fraction of the H_2S present in the overhead system. Thus the NH_3 withdrawn as a vapor in line 24 is substantially freed of H_2S . The H_2S content in the NH_3 vapor is generally less than about one to two percent and may be reduced to as low as 0.1 to 0.5 percent H_2S by volume. The condensate which is formed by cooling the NH_3 stripper overhead vapors in condenser 21 is rich in NH_3 . Typically, the ratio of NH_3 to H_2S will be between 10:1 and 2:1 in the condensate withdrawn from reflux drum 23 via line 25. Preferably, the ratio of NH_3 to

H_2S is between 3:1 to 6:1 on a molar basis. A portion of this NH_3 -rich condensate is refluxed to the NH_3 stripper via line 27 to provide cool, downward flowing liquid in the upper part of the NH_3 stripper. According to the process of the present invention, a second portion of the NH_3 -rich condensate is recycled via line 26 to be combined with the net feed introduced to the process via lines 1 and 2.

In the present invention it is preferred to control the amount of NH_3 -rich condensate which is recycled, as well as the ratio of NH_3 to H_2S in the recycle, so that the ratio of NH_3 to H_2S of the combined streams fed to the high pressure degasser is at least 1.1:1.0 on a molar basis. For streams which contain more than a percent or two of dissolved NH_3 and H_2S it is preferable to use more recycle NH_3 -rich condensate, so that the ratio of NH_3 to H_2S (calculated as separate species) is at least 1.2 to 1.0, and in many instances it is preferred to have as much as one and one-half to about five times as much NH_3 as H_2S .

EXAMPLE

This example illustrates the advantages obtained using the process of the present invention for treating aqueous streams which contain large amounts of H_2S relative to NH_3 in addition to light hydrocarbons and/or hydrogen dissolved in the aqueous stream due to high pressure.

A solution comprised of about 984 pounds of H_2S , 516 pounds of NH_3 , and about 760 standard cubic feet of hydrogen plus light hydrocarbons dissolved in 27,820 pounds of H_2O is obtained by water washing a hydrocracker reactor effluent. The hydrocracker reactor effluent stream which is water washed is at about 250° F. and 1,250 p.s.i.g. The aqueous stream thus obtained is introduced via line 1 to the process schematically illustrated by the drawing, except that there is no recycle NH_3 -rich condensate to the high pressure degasser. Part of the NH_3 -rich overhead from the NH_3 stripper is, however, recycled directly to the H_2S stripper.

An aqueous solution comprised of 28,000 pounds of H_2O , 436 pounds of H_2S and only trace amounts of NH_3 is obtained as overhead condensate from a fractionating column in the fractionation section of the hydrocracking unit. This stream is introduced via line 2 to the process. In this first instance, the NH_3 -rich condensate from the overhead of the NH_3 stripper is recycled directly to the H_2S stripper. The above streams and the resulting streams corresponding to the numbered streams shown in the drawing are summarized in the table below:

TABLE I

Stream No.	H_2O , lb./hr.	H_2S , lb./hr.	NH_3 , lb./hr.
1	27,820	984	516
2	28,000	436	0
3	55,820	1,420	516
5	2	390	0
8	55,818	1,030	516
10	1	10	0
11	55,817	1,020	516
15	6	1,010	0
24	3	5	499

The combined streams 5 and 10 contain about 760 s.c.f. of hydrogen plus light hydrocarbons.

Using the process of the present invention, identical streams 1 and 2 are fed to the process schematically illustrated in the drawing. In addition, a portion of the condensed overhead from the NH_3 stripper 18 is recycled via line 26 to the high pressure degasser. This recycle stream is rich in NH_3 relative to H_2S . The moles NH_3 in the recycle stream are 26.2; the moles H_2S total 8.7, thus resulting in a molar ratio of NH_3 to H_2S of about 3.01. There is sufficient NH_3 in the NH_3 recycle via line 26 so that the resulting combined streams in line 3 have a ratio of NH_3 to H_2S on a molar basis greater than 1.0. Preferably, the ratio of NH_3 to H_2S in stream 3 is maintained above 1.1.

In this example, the ratio of NH_3 to H_2S is 1.22. The feed streams and resulting streams are summarized below:

TABLE II

Stream No.	H_2O , lb./hr.	H_2S , lb./hr.	NH_3 , lb./hr.
5	27,820	984	516
2	28,000	436	0
26	568	148	444
3	56,388	1,568	960
5	1	2	0
8	56,388	1,564	960
10	1	2	0
11	56,387	1,562	960
15	6	1,406	0
24	3	5	499

The combined streams 5 and 10 contain about 760 s.c.f. of hydrogen plus light hydrocarbon gases.

As can be seen from the comparison of streams 5 and 10 in Table II to streams 5 and 10 in Table I, the H_2S losses are drastically reduced. Using the process of the present invention, the H_2S losses are reduced from 400 pounds per hour (Table I) to 4 pounds per hour (Table II). Thus the process of the present invention results in reducing the H_2S present in the flashed off gases by a factor of 100 in this example. Thus recycling NH_3 -rich overhead condensate from the NH_3 stripper is of particular advantage when feeding streams which have relatively large amounts of H_2S compared to NH_3 . When the H_2S concentrations in the net feed streams are lower, the advantage is correspondingly reduced, but generally the H_2S loss is reduced by a factor of at least five. Also, the recycle of the NH_3 -rich condensate will still serve to some degree to help retain H_2S in the aqueous phase so that it may be recovered via line 15 as a unitary product stream. Furthermore, the recycling of NH_3 -rich condensate to the degassing section instead of directly to the H_2S stripper has the very important advantage of improving control stability of the H_2S stripper and the NH_3 stripper.

Although various specific embodiments of the invention have been described and shown, it is to be understood they are meant to be illustrative only and not limiting. Certain features may be changed without departing from the spirit or essence of the invention. It is apparent that the invention has broad application to the recovery of separate streams of H_2S and NH_3 from aqueous solutions of the same. Accordingly, the invention is not to be construed as limited to the specific embodiments illustrated but only as defined in the following claims.

I claim:

1. A process for separately recovering an H_2S -rich stream and an NH_3 -rich stream from a first aqueous solution comprising H_2O , H_2S , NH_3 and dissolved methane under superatmospheric pressure according to the steps:

(a) combining at least a portion of an NH_3 -rich overhead condensate with the first aqueous solution to obtain a combined aqueous solution having a molar ratio of NH_3 to H_2S of at least 1.1 moles NH_3 to 1.0 moles H_2S ;

(b) removing from the combined aqueous solution at least 80 volume percent of the dissolved methane as a gas by reducing the pressure on the combined aqueous solution to a pressure at least below 200 p.s.i.g. to thereby flash off methane;

(c) providing at least one hour residence time for the combined aqueous solution; and then

(d) passing the combined aqueous solution to a first distillation column;

(e) stripping H_2S out of the second aqueous solution in the first distillation column to obtain an H_2S -rich overhead stream and an aqueous bottoms stream of reduced H_2S content;

(f) stripping NH_3 out of the aqueous bottoms stream of reduced H_2S content in a second distillation column to obtain an NH_3 -rich vapor overhead; and

(g) partially condensing the NH_3 -rich vapor overhead to obtain an NH_3 -rich vapor stream and said NH_3 -rich overhead condensate.

2. A process according to claim 1, wherein between about 3 and 24 hours residence time is provided for the combined aqueous solution before passing the combined aqueous solution to the first distillation column.

3. A process according to claim 1, wherein at least 24 hours of residence time is provided for the combined aqueous solution before passing the combined aqueous solution to the first distillation column. 5

4. A process according to claim 1, wherein the combined aqueous solution is degassed first in a high pressure degasser at a pressure between 50 and 500 p.s.i.g. and then is degassed in a low pressure degasser at a pressure between 0 and 50 p.s.i.g. 10

5. A process according to claim 4, wherein the combined aqueous solution is degassed first in a high pressure degasser at a pressure of between 70 and 200 p.s.i.g. and then is degassed in a low pressure degasser at a pressure between 1 and 10 p.s.i.g. 15

6. A process according to claim 4, wherein the gross feed to the high pressure degasser is comprised of:

(a) an aqueous solution of H_2S , NH_3 , light hydrocarbons, and hydrogen (stream *a*) obtained by contacting with water the effluent from a hydroconversion process at a pressure of at least 500 p.s.i.g.,

(b) an aqueous solution comprised of H_2S and light hydrocarbons (stream *b*), wherein the H_2S content is such that the combined streams (*a*) and (*b*) have

an NH_3 to H_2S molar ratio less than 1.1:1.0, and (c) the NH_3 -rich condensate stream (stream *c*) from the overhead of the NH_3 stripper, and wherein the amount of NH_3 in the NH_3 -rich condensate recycled from the overhead of the NH_3 stripper is sufficient so that the combined streams (*a*), (*b*) and (*c*) have an NH_3 to H_2S molar ratio of at least 1.1:1.0.

UNITED STATES PATENT OFFICE
CERTIFICATE OF CORRECTION

Patent No. 3,518,166

June 30, 1970

Robert J. Klett

It is certified that error appears in the above identified patent and that said Letters Patent are hereby corrected as shown below:

Column 2, lines 5 thru 9 should be deleted and the following inserted instead therefor -- action effluent, a portion of these light hydrocarbons, as well as a small portion of the hydrogen, will dissolve in the water phase, particularly if the washing is at a high pressure. In many hydroconversion processes, the washing is done at a pressure of 500 to 5,000 psig, more --.

Signed and sealed this 20th day of October 1970.

(SEAL)
